(57) **CLAIM**

The ornamental design for a motor housing for snow-thrower, as shown and described.

DESCRIPTION

FIG. 1 is a top, left, and front perspective view of a motor housing for snowblower shown in environmental use; FIG. 2 is a top, left, and front perspective view of a motor housing for snowblower; FIG. 3 is a front elevation view of that shown in FIG. 2; FIG. 4 is a left side elevation view of that shown in FIG. 2; FIG. 5 is a right side elevation view of that shown in FIG. 2; FIG. 6 is a rear elevation view of that shown in FIG. 2; FIG. 7 is a top plan view of that shown in FIG. 2; and, FIG. 8 is a bottom plan view of that shown in FIG. 2. The dash-dash broken lines represent environmental subject matter and form no part of the claimed design. The dot-dash broken lines define the bounds of the claimed design and form no part thereof.
